ADJUSTABLE LINK

Albert J. Gore, Washington, D. C.

Application November 12, 1943, Serial No. 510,083

3 Claims. (Cl. 287—77)

This invention relates to adjustable links and more particularly to links that may be adjusted to any desired length and when so adjusted will withstand any desired pressure or tension in either direction.

One of the objects of the present invention is to provide a link of the above character which will be of simple and practical construction and easy to manufacture by automatic machinery.

A further object is to provide a device of the above character which may be easily adjusted to any desired length with the assurance that it will remain at that length under stress in either direction.

A further object is to provide a device of the above character which may be easily manufactured and installed as desired in a variety of places in a manner similar to a turnbuckle now in extensive use.

Other objects will be in part obvious from the annexed drawing and in part thereafter indicated in connection therewith by the following analysis of this invention.

The invention accordingly consists in the features of construction, combination of parts, and in the unique relation of the members and in the relative proportioning and disposition thereof, all as more completely outlined herein.

To enable others skilled in the art fully to comprehend the underlying features of this invention, that they may embody the same by the numerous modifications in structure and relation contemplated by the invention, drawing depicting some preferred embodiment of the invention forming a part of this disclosure, and in such drawing like characters of reference denote corresponding parts throughout the several views, in which—

Fig. 1 is a side elevation of the device in locked position.

Fig. 2 is a similar view of the same parts in released position ready to be adjusted.

Fig. 3 is an end view of the right-hand part as shown in Fig. 1.

Fig. 4 is a similar view of the same part as shown in Fig. 2.

Fig. 5 is a partial sectional view of a modified form of one part.

Fig. 6 illustrates a safety lock arrangement of the link.

Fig. 7 illustrates a different safety lock modification.

In order that a clearer understanding of the present invention may be had let us assume that the present invention is applicable in any

place where the usual turnbuckle may be employed and it is desired to position the adjustable link hereinafter described in a place and association to withstand any reasonable push or pull that may be exerted on the ends thereof. Obviously it is unnecessary to recite the uses to which such an adjustable link might be put.

While the above figures do not illustrate any particular use, let us assume that the part 10 denotes one end of one part which may be shaped in any desired manner to best coact with one spaced member not shown which is adapted to be adjusted or coacting therewith relatively to another member not shown but connected as desired and necessary to end of the part 11. Between the parts 10 and 11 is the adjustable connection indicated by the parts 12 and 13 of the link. For convenience these parts are made of wire of the desired size according to the use and strain to which the link is to be used.

The part 12 terminates in a series of wave-like formations 14 preferably all lying in the same vertical plane as shown. These waves may be termed zig-zag.

The free end of the part 13 terminates in an elongated loop 15 shown in Figs. 3 and 4. That is, this loop is about twice as long as it is wide and for convenience of illustration in Fig. 3 the major axis is at right angles to the plane of the waves 14. Thus when the parts are in the position shown in Figs. 1 and 3 the minor axis of this hook engages any part of the wave-like portion 14 and resists pressure in either direction while if given a 90° turn then the minor axis of the loop 15 is at right angles to the plane of the zigzag Figs. 2 and 4. The loop is then free to move in either direction to effect the desired adjustment to the position at which the parts 10 and 11 are separated to the desired extent whereupon the parts 10 and 11 are rotated relatively 90° or back to the position shown in Figs. 1 and 3 and the parts of the link are locked in the desired adjusted position to resist force in either direction.

In Fig. 5 there is shown a modification that is, a swivel 16 of any desired style may be interposed in either part indicated by the numerals 12 or 13 Fig. 1, preferably the turnable part, at the places adjacent such lead lines to 13 in Fig. 1. That is, for example, the part 13 is divided into two parts 13a and 13b with the swivel 16 therebetween thus permitting these parts 13a and 13b to be turned 90° and perform the same function as though the part 13 were rotated an equal amount to turn the loop 15 whereby its

major axis is in the plane of the zigzags 14 of the part 12 as shown.

A safety lock may be provided as shown in Fig. 6, that is the part 13 may be depressed between the crests of any two adjacent zigzags 14 which cause the parts in contact to bind at 17 to prevent further any chance of slippage between the effective ends 10 and 11, Fig. 1 irrespective of the position of the loop 15 on the up or down slant of any zigzag, thus insuring a positive lock of the parts in any adjusted position.

In Fig. 7 there is shown a further modification in which the part 12 as shown in Fig. 1 is herein designated as 12a and the construction of that part is the same. However, instead of having a free end at the right as shown in Fig. 1 this is continued back on itself like a hairpin and designated as 12b, the end of which terminates in a hook or other fastening device engaging the end of the device 11. The purpose of this construction is positively to prevent any change in length of the part 12a which might occur if an abnormal strain were exerted upon this part in either direction tending to compress or elongate the wave-like formation. The co-operating part 13 is not shown but is the same as in Fig. 1, for example.

The operation of the device is obvious from the above but it may be stated that the adjustable link is positioned between any two parts the relative position of which parts is to be secured. Such parts with the link in the position shown in Fig. 2 or Fig. 4 are moved to the desired separating distance and then the part 10 or 11 turned effectively through 90° until the long axis of the loop 15 is at right angles to the plane of the zigzags or waves 14 (Fig. 3) whereupon any movement in either direction is prevented due to the binding action of adjacent points in the two parts of the adjustable links and to lock these parts in adjusted position, after which the part 13 may be depressed between any two adjacent crests (Fig. 6) so that there is absolutely no danger of slippage under any circumstances. It is to be understood that the device may be used as a brace or tie between

any two fixed parts and positioned at the desired length between such parts and then locked in such position in the manner above described.

It is thus seen that the present invention provides a simple and practical adjustable link well adapted to accomplish all of the objects and advantages herein set forth.

Without further analysis the foregoing will so fully reveal the gist of this invention that others can, by applying current knowledge, readily adapt it for various applications without omitting certain features that, from the standpoint of the prior art, fairly constitute essential characteristics of the generic or specific aspects of the invention, and, therefore, such adaptations should and are intended to be comprehended within the meaning and range of equivalency of the following claims.

I claim:

1. An adjustable link comprising two parts one of which includes a series of wave-like bends, and the other having an elongated looped end engaging said bends, which when turned to a position in which when the minor axis of the loop is transverse to the plane of the bends tends to bind thereby to prevent relative movement of the parts in either direction but when the major axis of the loop is in the plane of the bends permits the parts to move freely with respect to each other.

2. An adjustable link comprising two parts one of which includes a series of reverse bends in the same plane, and the other having an elongated loop engaging said bends, which when turned in one position tends to bind thereby to prevent relative movement of the parts in either direction but when turned from such position permits the parts to move freely with respect to each other.

3. A device as set forth in claim 2 in which the portion with the bends is provided with an extension parallel with the axis of the portion having the bends and attached at its end to the portion having the bends, thereby resisting any force tending to vary the size of the bends.

ALBERT J. GORE.
